John E. Hubbard
ATTORNEY

UNITED STATES PATENT OFFICE.

THOMAS BUTERA, OF BROOKLYN, NEW YORK.

TAILOR'S KIT.

Application filed August 25, 1926. Serial No. 131,376.

The general object of my present invention is to provide an improved device of simple construction and compact form for holding articles or implements. More specifically the object of my present invention is to provide a unitary plate-like tailor's kit constructed and arranged to receive and hold several tailoring implements and adapted to receive means for securing it to the arm 10 of the user.

The various features of novelty which characterize my invention are pointed out with particularity in the claims annexed to and forming a part of this specification. 15 For a better understanding of the invention, however, and the advantages possessed by it reference should be had to the accompanying drawings and descriptive matter in which I have illustrated and described a 20 preferred embodiment of the invention.

Of the drawings:

Fig. 1 is a perspective view of my device showing the various implements in position;

Fig. 2 is a section on the line 2—2 of Fig. 25 1 with the implements removed; and

Fig. 3 is a plan view of a partially manufactured plate.

My invention consists of a plate member having a plurality of prongs formed thereon, arranged to receive and hold several tailoring implements and, adapted to be 30 worn on the wrist of the user.

In the preferred form of the invention as shown by the drawings, the tailoring kit is 35 in the form of a plate member A of substantially rectangular shape and having its corners rounded off. The plate member is slightly curved to substantially conform to the curvature of the wrist of the user. In 40 one-half of the plate A is provided a plurality of symmetrically arranged outwardly projecting thimble holding prongs A', each of which is curved convexly and provided with a multiplicity of small projections A". 45 The prongs A' are arranged in angularly spaced relation to receive a thimble B, the closed end of which is inserted between the prongs. The thimble B is held in position 50 by the elasticity of the curved prongs and by the fact that some of the projections A" engage in indentations B' in the outer surface of the thimble. Each prong is tapered upwardly from its base as shown to strengthen the construction sufficiently to

withstand the constant insertion of the 55 thimble. The prongs are adapted to receive thimbles of various sizes. The degree of curvature of the prongs A' is dependent on the size of the thimble in use. For example, for a large sized thimble the curved 60 portion of the prongs begins closer to the prong base than when a smaller thimble is in use.

In the other half of the plate A and near one edge thereof is provided a projecting 65 C-shaped member A³ arranged to receive a basting puller C. The basting puller is held in position by the resiliency of the projecting member. On the remaining portion of the plate A is glued, cemented or 70 otherwise secured a cushion A⁵ of rectangular shape and adapted to receive needles and pins D. Along each end portion of the plate A is a narrow longitudinal slot A⁴, through which a strap E may be passed to 75 secure the plate on the wrist of the user.

In the ordinary manufacture of my device a piece of light sheet metal is first converted by the action of a stamping machine into the blank form as shown in Fig. 80 3 with the thimble holding prongs A' having the projections A² therein symmetrically arranged and cut out portions between the prongs in the general shape of a four leaf clover. The cut out portions permit 85 the closed end of the thimble to be inserted between the prongs to a greater extent than if the prongs were formed without such portions. All of the plate openings serve 90 as passages for air circulation to the underside of the plate. The substantially U-shaped slot forming the baster holder A³ and the narrow strap slots A⁴ may be formed in the same stamping operation. The thimble holding prongs and baster 95 holder are then bent into the proper shape and the cushion A⁵ secured to the plate member A. The strap E or other suitable holding means is then passed through the slot A⁴. 100

My device is of simple and compact construction, easy and cheap to manufacture and especially useful for tailors, the parts being so arranged that the articles and implements most used in the tailoring trade 105 are close at hand and ready for use. The feature of having a unitary holder for several implements in intermittent but constant

use obviously results in increased efficiency and eliminates the time lost in searching for articles mislaid. Constructing the plate with the strap slots so that the plate may be 5 worn on the wrist of the user is advantageous as a tailor usually carries such implements about with him. The plate is usually strapped onto the left wrist of the user as a needle worker ordinarily handles 10 the implements with his right hand, using his left hand for adjusting the work. The user can carry the plate on his wrist without discomfort or annoyance as the strap passing behind the plate and the ventilation 15 permitted by the cutout plate portions serve to prevent any chafing of the wrist by the plate. The construction of the curved prongs integral with the plate permits the use of light sheet metal as the curved members 20 strengthen the plate against stresses transverse to the bending axes.

While in accordance with the provisions 25 of the statutes, I have illustrated and described the best form of embodiment of my invention now known to me, it will be apparent to those skilled in the art that changes may be made in the form of the apparatus disclosed without departing from the spirit of my invention as set forth in 30 the appended claims and that in some cases

certain features of my invention may be used to advantage without a corresponding use of other features.

Having now described my invention, what I claim as new and desire to secure by 35 Letters Patent is:

1. An article holder adapted to be carried on a wrist of the user comprising a plate having a plurality of integral prong members projecting from one side thereof, 40 said members cooperating to receive and hold a sewing implement between said members, and a narrow slot extending along opposite side edge portions of said plate and adapted to receive a fastening member. 45

2. An article holder adapted to be carried on a wrist of the user comprising a plate having a plurality of projecting curved prong members symmetrically arranged on and integral with said plate, a 50 multiplicity of projections on the inner side of each of said members adapted to contact with the outer surface of a sewing implement held therebetween, and means for securing said plate on the wrist of the user. 55

Signed at Brooklyn, in the county of Kings and State of New York, this 20th day of August, A. D. 1926.

THOMAS BUTERA.
